UNITED STATES PATENT OFFICE.

ARTHUR J. MORSE, OF SALISBURY, CONNECTICUT, ASSIGNOR TO THE MORSE-KEEPER CYCLE SUPPLY COMPANY, OF SAME PLACE.

SWAGING-MACHINE.

SPECIFICATION forming part of Letters Patent No. 588,649, dated August 24, 1897.

Application filed March 12, 1897. Serial No. 627,194. (No model.)

To all whom it may concern:

Be it known that I, ARTHUR J. MORSE, of 5
Salisbury, in the county of Litchfield, in the
State of Connecticut, have invented new and
useful Improvements in Swaging-Machines,
of which the following, taken in connection
with the accompanying drawings, is a full,
clear, and exact description.

My invention relates to improvements in
10 swaging-machines for swaging bicycle-spokes,
needles, and analogous articles; and the ob-
ject is to provide means whereby the cams or
tappets may be quickly, equally, and sim-
15 taneously adjusted, and the friction decreased
between said cams or tappets and the die-
blocks or backers.

To this end my invention consists in the
combination, with the stationary cylindrical
20 shell, of a circular series of cams movable ra-
dially in grooves in said shell, an adjustable
ring mounted on the shell and provided with
a series of inclined recesses to engage the
cams, a cylindrical shaft in said shell carry-
25 ing a rotary head containing a groove, a pair
of dies, and a pair of die-blocks in said groove
and a roller in each die-block to engage the
cams; and my invention consists also in cer-
tain other combinations of parts hereinafter
30 described, and specifically set forth in the
claims.

In the drawings hereto annexed and forming
35 a part of this specification, Figure 1 is a
side elevation, partly in section, of my im-
proved swaging-machine. Fig. 2 is a face
view of the rotary head. Fig. 3 is a side ele-
vation of the rotary head removed from the
40 shell. Fig. 4 shows a face view of the dies,
die-blocks, and rollers removed from the head.
Fig. 5 shows dies and die-blocks without roll-
ers. Fig. 6 is an enlarged face view of the
head of the swaging-machine with the face-
45 plates removed, and Fig. 7 shows the same
with the face-plates and the adjustable plate
secured thereto.

Referring specifically to the drawings, A is
the stationary cylindrical shell or casting, one
50 end of which is expanded to contain the ro-
tatable head.

B' is the rotatable head, and B is the cylin-
55 drical driving-shaft of the head, which ex-
tends horizontally and longitudinally within

the shell. Across the end of the said head is
a mortise or groove, and in the groove is a
pair of sliding dies b b, a pair of die-blocks
or backers b' b', and a roller c in each die-
block to engage the beveled ends of the cams
a a, &c.

In order to secure the dies, die-blocks, and
rollers in the groove of the head B', I secure
a small plate d to the face of the head over
60 the groove. This plate d is shown let into the
head so that its face is flush with that of the
head.

In the face of the expanded end of the shell
are a series of radial grooves, and in these
65 grooves are the movable tappets or cams a a,
&c. The inner ends of the cams are beveled
or inclined and engage the small rollers c c
in the ends of the die-blocks. The outer ends
70 of the cams are also beveled and engage the
series of inclined surfaces or recesses a' a',
&c., formed on the inner surface of the adjust-
able ring C, mounted on the periphery of the
expanded portion of the shell. Said recesses
75 in the ring are all inclined in the same direc-
tion corresponding with the beveled ends of
the cams, so that when it becomes necessary to
move the cams toward the rotary head more
or less this may be accomplished by moving
80 or rotating the ring C upon the shell. To ef-
fect this movement easily, I preferably pro-
vide the ring with a lug D, to which is at-
tached a handle D'. The unfeathered arrow
near the lug indicates the direction of move-
85 ment of the ring when the cams are forced
toward the center. It will be obvious that by
these means the cams will be moved simulta-
neously and equally.

In order to secure the cams a a, &c., in the
grooves, I secure, by means of screws or bolts,
90 a pair of ring-shaped face-plates E F to the
face of the stationary head. The face-plates
differ in size and are concentric with each
other. Between the said face-plates is an ad-
justable ring-shaped face-plate G, provided
95 with a series of slots e equal in number to
the cams. These slots engage the cams a by
means of pins f, projecting from the cams and
entering the slots. The slots are slightly
curved and tangential, so that when the plate
100 is rotated with the ring C, to which it is con-
nected by a lug g and screw g', passing

through a slot *h* in the face-plate *E*, it will also aid in moving the cams *a a*, &c. The movable face-plate serves to move the cams outward away from the center when the ring *C* is moved in the direction to permit of such movement. Plate *G* is provided with beveled edges which engage beveled edges on the stationary plates.

During the revolution of the head there are 10 as many closures of the dies each revolution of the shaft as there are tappets or cams in the circular series. The cams are diametrically opposite each other, and this insures a stroke upon both die-blocks or backers simultaneously.

I preferably provide the die-blocks with the rollers *c c*, as they decrease the friction to a considerable degree, but I do not desire to be limited to them, as the die-blocks themselves 20 may be provided with curved ends, as shown in Fig. 5, and directly engage the cams.

In Fig. 1, *H* is the driving-pulley, and *I* is the loose pulley on the shaft *B*.

Having described my invention, what I 25 claim as new, and desire to secure by Letters Patent, is—

1. In a swaging-machine, the combination with the stationary cylindrical shell, of a circular series of cams movable radially in 30 grooves in said shell, an adjustable ring mounted on the shell and provided with a series of inclined faces to engage the cams, a stationary face-plate to retain the cams in their grooves, an adjustable face-plate provided with tangential slots, pins projecting from the cams and entering the slots, a rotary shaft carrying a head with a groove and dies and die-blocks in the groove, as set forth.

2. In a swaging-machine, the combination 35 with the stationary cylindrical shell, of a cir-

cular series of cams movable radially in grooves in said shell, an adjustable ring mounted on the shell and provided with a series of inclined faces to engage the cams, a stationary face-plate to retain the cams in 45 their grooves, an adjustable face-plate provided with tangential slots, pins projecting from the cams and entering the slots, a connection between the adjustable face-plate and the adjustable ring, means carried by the said 50 ring for moving the same, a rotary shaft carrying a head with a groove and dies and die-blocks in the groove adapted to be operated by the cams, as set forth.

3. In a swaging-machine, the combination 55 with the stationary cylindrical shell, of a circular series of cams movable radially in grooves in said shell, an adjustable ring mounted on the shell and provided with a series of inclined faces to engage the cams, a 60 pair of stationary concentric face-plates to retain the cams, a circular adjustable face-plate between the stationary plates, said adjustable plate having tangential bearing-surfaces, pins projecting from the cams and engaging the said bearing-surfaces, a connection 65 between the adjustable plate and the adjustable ring, means on the ring for turning the same, a rotary cylindrical shaft carrying a head provided with a groove, dies 70 and die-blocks in the groove, rollers in the end of the die-blocks to engage the cams, and a plate covering the groove and secured to the head, as and for the purpose described.

In testimony whereof I have hereunto 75 signed my name.

ARTHUR J. MORSE. [L. S.]
